UNITED STATES PATENT OFFICE

91,119

DESIGN FOR A COMBINED SPONGE CUP AND APPLICATOR

Louis Nassif, Wheeling, W. Va.

Application March 2, 1933. Serial No. 47,390

Term of patent 7 years

To all whom it may concern:

Be it known that I, LOUIS NASSIF, a citizen of the United States, residing at Wheeling, in the county of Ohio and state of West Virginia, have invented a new, original, and ornamental Design for a Combined Sponge Cup and Applicator, of which the following is a specification, reference being had to the accompanying drawing, forming part thereof, wherein,

Figure 1 is a side elevation of the sponge cup and applicator.

Fig. 2 is a top plan view of the device.

I claim:

The ornamental design for a combined sponge cup and applicator, as shown.

LOUIS NASSIF.
